UNITED STATES PATENT OFFICE.

LEONARD E. TRAVIS, OF NEWARK, NEW JERSEY, ASSIGNOR TO THE ARTELL COMPANY, A CORPORATION OF NEW YORK.

SOAP-HOLDER.

No. 890,392

Specification of Letters Patent.

Patented June 9, 1908.

Application filed February 26, 1906. Serial No. 302,921.

To all whom it may concern:

Be it known that I, LEONARD E. TRAVIS, a citizen of the United States, residing in the city of Newark, State of New Jersey, have invented certain new and useful Improvements in Soap-Holders, of which the following is a specification, reference being had to the drawings accompanying and forming a part of the same.

10 My invention relates to soap-holders and has for its object to provide means for causing the water to come in contact with the soap and issue from the soap holder in the form of a lather or suds.

15 Attempts have been made heretofore to produce a soap holder of this character, but so far as I am aware they have failed, because they have not recognized certain essential principles which are embodied in my 20 invention. In order to produce a lather or suds in a device of this character, it is necessary for the water to contact with the soap in the presence of air, otherwise the mixture will issue in the form of a solution of soap, as 25 distinguished from a lather or suds and will, therefore, be less effective.

30 In the accompanying drawings, I have shown means for accomplishing this object, Figure 1 being a vertical section and Fig. 2 a top plan view.

35 Water enters from the pipe A which may be connected to the source of supply in any convenient manner. This pipe terminates in a number of small orifices B which direct fine streams of water against the cake of soap C. The soap is held in a soap case which has a cap D, removable, so that the soap may be placed in the soap case, and a wire gauze or perforated metal bottom E, so that 40 the water may readily pass to and from the soap case. The soap case is supported in a shell F which serves to inclose the parts and form the nozzle G. The portion immediately surrounding the soap has a number of 45 perforations H, which serve to admit air to the interior of the shell, but not the escape of water.

It will be seen that the operation of my

invention, as embodied in this particular structure, is as follows: Water entering 50 through the pipe A issues from the nozzles B in fine streams, which impinge on the soap in the presence of air which enters through the perforations H and this mixture issues from the nozzle G in the form of a lather or 55 suds.

Having described my invention, what I claim is:

1. In a soap holder, the combination of a case containing soap, means for impinging 60 water on the soap in the presence of air, a shell surrounding said case and forming an outlet for the water and openings in said shell to admit air around said soap case, substantially as set forth.

2. In a soap holder, the combination of a case containing soap, said case having a removable cap and openings to admit water, means for impinging water on said soap in the presence of air, a shell surrounding said 70 case and forming an outlet for the water, and openings in said shell to admit air around said soap case, substantially as set forth.

3. In a soap holder, the combination of a 75 case containing soap, means for impinging water in finely divided streams on said soap in the presence of air, and means for carrying off in the presence of air the soap solution and soap suds thus formed, substantially as set forth.

4. In a soap holder, the combination of a case containing soap, means for impinging water in finely divided streams on said soap in the presence of air, a shell surrounding 85 said case and forming an outlet for the water, and openings in said shell to admit air around said soap case, substantially as set forth.

In witness whereof, I have hereunto set 90 my hand this 30th day of July, in the year nineteen hundred and four (1904).

LEONARD E. TRAVIS.
